Application June 20, 1951, Serial No. 232,626

11 Claims. (Cl. 226—125)

1
This invention relates to a device for use in filling refillable dispensing guns with flowable plastic material from containers.

Heretofore it has been the practice to supply flowable plastic material, such as lubricating grease, soaps, caulking compounds and the like, in a cylindrical container having an open end of the same diameter as the interior of the container. For filling dispensing guns from such containers a piston head or disc of the same external diameter as the interior diameter of the container is provided. The piston head has a central axial opening therethrough surrounded by a stem, which may be in the form of a rudimentary annular shoulder. The piston head is placed in the container with one face juxtaposed against the upper surface of the plastic material and the open end of the dispensing gun barrel, with the usual nozzle removed, is engaged with the stem. In this position, the gun barrel and piston head are forced downwardly, the plunger in the gun being retracted concurrently, thus forcing the plastic through the central opening into the gun barrel. In some instances, adapters are provided for adapting the stem for fitting engagement with gun barrels of different diameters. Usually a removable cap is provided for the stem so as to seal the central opening.

After filling the gun barrel, the piston head, with its closure cap installed, is left in the can in direct contact with the upper surface of the plastic material, thus effectively excluding air and eliminating "crusting" of the upper surface of the plastic material.

Typical examples of such prior devices are disclosed in United States Letters Patent to Stowbridge, No. 1,739,266, of December 10, 1929; Eberhard, No. 2,301,933, of November 17, 1942, and Eckman, No. 2,517,551, of August 8, 1950. All such prior devices require a container of which the opening in the end is of the same size and shape as the internal cross section of the container.

On the other hand, suppliers of the plastic have found it more economical and otherwise desirable to package the material in the conventional paint can or bucket. Such a bucket has an inturned radially extending corrugated rim or flange at the open end arranged to cooperate, for sealing the container, with a press fitted cap which extends into the restricted end opening defined by the rim. With such containers the prior pistons cannot be used because if made small enough in diameter to pass through the restricted end opening there is too much clearance between the per-

2
iphery of the piston and the interior wall of the container.

The present invention resides in a piston device for the purposes described of which the piston is of such size and shape that it can be inserted through the open end of a paint container or bucket of the type having its open end restricted by an inturned radial rim, and a plurality of elements which are associated with the head and also are insertable through the restricted open end, and are movable relative to the head and to each other within the container into a position such as to render the head substantially the same size and shape as the cross section of the interior of the container.

More specifically, the present invention includes a plurality of such movable elements which detachably engage the piston head and can be inserted individually through the restricted end opening and assembled within the container in juxtaposition with the surface of the material so as to form an annulus fitting the internal cross section of the can, and when so arranged, the resultant annulus can be engaged in coaxial relation by the piston head and moved thereby, and therewith as a unit, toward the bottom of the container.

Various specific objects and advantages of the present invention will become apparent from the following description of a number of embodiments of the invention wherein reference is made to the drawings, in which:

Fig. 1 is an exploded perspective view of a device embodying the preferred form of the present invention;

Fig. 2 is an assembled perspective view, partly in section, of the device illustrated in Fig. 1;

Fig. 3 is a cross sectional view taken on line 3—3 of Fig. 2;

Fig. 4 is a side elevation, partly in section, illustrating a conventional paint container filled with plastic material, a dispensing gun, and the device of the present invention in cooperative relation to each other;

Fig. 5 is a perspective view of a modified form of the device;

Fig. 6 is a sectional view taken on line 6—6 of Fig. 5;

Fig. 7 is an exploded perspective view of another modified form of the device;

Fig. 8 is a sectional view taken as indicated by the line 8—8 of Fig. 7 but showing all of the parts of the device in assembled relation; and

Fig. 9 is an exploded perspective view respectively of another modified form of the device;

Fig. 10 is a perspective view of the parts of another modified form of the device;

Fig. 11 is an exploded perspective view of another modified form of the device;

Fig. 12 is a sectional view of the device, taken as indicated by the line 12-12 of Fig. 11, but showing the parts in assembled relation;

Fig. 13 is an exploded perspective view of another modified form of the device; and

Fig. 14 is a sectional view of the device taken as indicated by the line 14-14 of Fig. 13, but showing the parts in assembled relation.

Referring first to Figs. 1 to 4, the preferred form of the device is illustrated and is shown in use with a dispensing gun 1 for filling the barrel 2 thereof with flowable plastic material 3 from the conventional paint bucket or container 4 of the type having its open end restricted by an inturned radial corrugated flange 5 with which the usual press fitted top, not shown, is engaged for originally sealing the container. The gun 1 is provided with the usual piston head 6 and piston rod 7 which extends through one end of the barrel 2. The opposite end of the barrel 2 is externally threaded, as indicated at 8, for detachably receiving the desired dispensing nozzle (not shown). The plastic material may be ejected from the gun by manually forcing the piston rod 7 toward the nozzle end of the barrel or, if desired, by admitting air under pressure into the barrel above the piston head 6 under the control of a valve operable by a trigger 9.

The present device comprises a multi-section piston structure, indicated generally at 10, the parts of which are shown in Fig. 1. The piston structure comprises a head 11 which preferably is annular and disc-like and has a central opening 12. The head 11 is provided with a stem 13 which may be in the form of a relatively short or rudimentary sleeve coaxial with the opening 12. Preferably, the head 11 and sleeve 13 are integral and formed of a relatively thin but stiff sheet of material such as steel or other metal.

The stem 13 is constructed and arranged for connection to the open end of the barrel of a dispensing gun. As illustrated in Fig. 4, a suitable connection is afforded by making the stem cylindrical and of such diameter that it can fit snugly within the open end of the barrel 2. Any of the usual sleeve type adapters (not shown) may be provided for operatively connecting the same stem to gun barrels of different diameters, respectively. The head 11 preferably is of slightly less diameter than the restricted end opening of the container defined by the flange 5 so as to be receivable therethrough flatwise while in coaxial relation to the container.

In use, however, it is necessary that the effective diameter of the piston head be substantially equal to the internal diameter of the container 4. For increasing the effective diameter of the head 11, a plurality of segmental head elements 14 are provided. Each element 14 preferably is of thin but stiff sheet material or metal and is small enough to be received through the restricted end opening of the container and laid flatwise on the upper surface of the plastic material 3 therein without digging it into the material even when the upper surface of the material is only a fraction of an inch from the open end of the container.

In the preferred form, three identical elements 14 are used, each being in the form of a

geometric sector of an annular disc and of such size that, when assembled in edge to edge abutting relation, they define an annular disc slightly greater in diameter than the head 11 and having a central opening 15 of substantially the same diameter as the opening 12. Aligning means are provided on the elements 14, respectively, and cooperating aligning means are provided on the head 11 and are interengagable with the aligning means of the elements for constraining the assembled elements 14 from movement radially out of their annular assembly.

A suitable aligning means may comprise bosses 16 on the elements 14 and apertures 17 in the head 11, the bosses and apertures being so arranged that, when the elements 14 are assembled in edge to edge abutting relation, as illustrated in Fig. 2, each boss 16 is received in and snugly fits an associated one of the apertures 17. Each boss 16 preferably is integral with its element 14 and is hemi-spherical in shape.

Thus each of the elements 14 can be passed individually and, in turn, through the restricted opening of the container while held flatwise or about parallel to the upper surface of the material 3 and dropped onto the surface thereof, whereupon the operator, by pressing on the boss 16, skids the element radially outwardly along the upper surface of the material 3 until its outer circumferential edge engages and fits the inner wall of the container 4. When all elements 14 are thus assembled into an annulus on top of the material, the head 11 is laid thereon with the apertures 17 aligned with the bosses 16 and then pressed downwardly flatwise. Due to the hemispherical shape of the bosses, a cam action is provided when they are engaged by the edges of the apertures so that the initial slight downward movement of the head 11 adjusts and positions the elements 14 sufficiently to overcome any slight discrepancies in their original position and forces them outwardly snugly against the inner wall of the container. Thus a piston structure having an expandible piston head means comprising the head 11 and elements 14 interengaged therewith, is provided.

In order to prevent tilting of the elements 14 flatwise about the outer peripheral edge of the head 11 due to the reaction forces of the material 3 when the piston head means is moved downwardly in the container, the elements 14 and head 11 are so related that the area of that portion of each element 14 juxtaposed against the head 11 is greater than the area of that portion of the element lying radially outwardly beyond the circumference of the head 11.

It is apparent from Figs. 1 to 4 and the foregoing description that a simple and effective piston structure with an expandible piston head means is provided.

As shown in Fig. 4, when the piston structure 10 is thus assembled within the container 4, the open end of the gun barrel 2 is telescopically engaged externally with the stem 13 with its lower edge bearing against the head 11. A close fit between the barrel 2 and stem 13 is not absolutely essential, however, as the engagement of the lower edge of the barrel with the head 11 forms a substantial seal considering that the interior of the barrel above the level of the material 3 is under sub-atmospheric pressure during filling of the gun.

With the piston structure and gun in the relation described, the barrel 2 is pressed downwardly and concurrently the piston rod 7 is op-

erated to lift the piston head 6. These forces cause the plastic material to flow into the barrel readily as a continuous compact mass of substantially uniform cross section and free from air bubbles.

Referring next to Figs. 5 and 6, a somewhat similar device 20 is illustrated and comprises an annular head 21 having a central opening 22, stem 23, and segmental head elements 24, corresponding to the head 11, opening 12, stem 13 and head elements 14 heretofore described.

In this form of the invention the head 21 is provided with apertures 25 and the elements 24 are provided with bosses 26 having projecting lips 27 spaced above the plane of the elements 24. Each boss 26 and its lip 27 preferably is a piece of sheet metal spot welded to the associated element 24. The bosses are slightly smaller than the apertures 25. When the elements 24 are assembled, the head 21 is installed by passing it downwardly until the lips 27 pass through the apertures 25, respectively, and then, while continuing the downward movement, by rotating the head 21 about its axis.

The lips are arranged so that, by this action, they engage the upper edges of the apertures and provide a cam action drawing the elements firmly against the under face of the head 21 and guiding them so that the bosses 26 enter the apertures 25.

In Figs. 7 and 8, another modified form of the invention is illustrated, wherein the piston structure may be assembled before insertion through the restricted end opening of the container. In this form, a head 31 having a central opening 32 and stem 33 corresponding to the head 11, opening 12 and stem 13 are provided. The head also has radial slots 34.

Segmental head elements 35, corresponding in function to the elements 14 are provided. However, the elements 35 are arranged so that alternate ones, taken circumferentially of the head, overlap those circumferentially adjacent thereto at their lateral margins, as indicated at 36. Each element 35 has a lug 37 extending through a complementary one of the slots 34 so as to slide endwise of the associated slot while guided thereby while the element is parallel to and close to or in contact with the under face of the head 34. Each lug 37 has a lip 38 overlying and in sliding contact with the upper face of the head 34, thus holding the elements 35 in assembled relation to the head 34 while permitting movement of each radially of the head 34.

Thus the piston head means comprising the head 34 and elements 35 is expandable and contractible radially. The elements 35 are moved to contracted position for insertion through the restricted end of the container and then are moved to expanded position by manipulation of the lugs. For moving all of the elements 35 concurrently to expanded position, a cam means is provided. The cam means may be in the form of a sleeve adapted to fit rotatably on and in coaxial relation with the stem 33 and having at one end a plurality of radially expanding cam surfaces 40 engageable with the lugs 37 respectively. Thus by rotating the sleeve 39 in one direction the cam surface cooperates with the lugs 37 to move the elements 35 radially outwardly. The elements 35 are preferably so shaped that when in expanded position their outer limit is circular and of the same diameter as the interior of the container.

The form illustrated in Fig. 9 is essentially the

same as that illustrated in Fig. 1 except that it employs segmental head elements which are of different shape than the elements 14. The piston structure of Fig. 9 comprises a head 41 with a central opening 42 and stem 43 corresponding to the head 11, central opening 12 and stem 13 of Fig. 1. Segmental head elements 44, however, are not geometric sectors of an annulus even though when assembled in edge to edge abutting relation they define an annulus. This form is merely to illustrate that various shapes of segmental head elements may be employed. Each element should have a boss 46 receivable in a complementary aperture 47 in the head 41.

In Fig. 10, the stem of the piston structure is formed on the segmental head elements instead of on the head. As there illustrated, the head 51 is in the form of an annulus having a central opening 52. The stem, indicated generally at 53, is formed in segments, one segment on each segmental head element 54. When the segmental head elements 54 are assembled in edge to edge abutting relation, the upright edges of the segments of the stem 53 also are in abutting relation thus providing a circumferentially closed stem. The head 51 is laid on top of the assembled elements 54 with bosses 56 of the elements received in apertures 57 of the head 51, the stem 53 being received through and snugly fitting the opening 52, thus providing a piston structure of which the piston head means is expandable.

Referring next to the modification shown in Figs. 11 and 12, the head is in the form of an upper annulus and a lower annulus. The lower annulus 61 has a central opening 62 surrounded by a stem 63. In this form, it is preferred that four segmental head elements 64 be used and assembled with their lateral margins in overlapping relation, as illustrated, on the upper face of the lower annulus. The upper annulus of the head is preferably in the form of a flat disc 65 of the same external diameter as the annulus 61 and of which the central opening 66 fits the stem 63.

In operation, the lower annulus is placed in the container on the upper surface of the material with the stem upward. The head elements are then inserted and laid on the upper surface of the annulus 61 in overlapping relation, and the annulus 65 then slid over the stem 63 so as to confine the elements 64 between the annuli.

In Figs. 13 and 14, a form the same as that illustrated in Figs. 11 and 12 is provided except that the upper, as well as the lower annulus, is provided with a stem. In this form, the upper annulus 71 has a central opening 72 surrounded by a stem portion 73. The head elements 74 are identical with the head elements 64. The lower annulus 75 has a central opening 76 surrounded by a stem portion 77.

The annuli 71 and 75 are identical. The stem portions 73 and 76 are slightly tapered upwardly so that they can be fitted together telescopically while the head elements 74 are assembled therebetween, as illustrated. The resultant tapered stem is of advantage in accommodating itself to, and providing a better fit with, the open end of the barrel of a dispensing gun, which, for a given size, varies slightly in internal diameter.

It is to be noted that in all forms of the invention in which the head is removable from the segmental head elements, the segmental head elements can be assembled by moving them normal and parallel to their planes so that they

do not have to be tilted and interfitted for assembly with or disassembly from each other. Likewise, the head with its stem can be assembled and disassembled with respect to the segmental head elements by corresponding movement and without tilting. Again, the heads, such as the head 11, may be varied considerably in shape and form so long as the cooperation between it and the segmental heads, as described, are retained, but the simple flat disc-like head is preferred.

The entire structure is simple in form, and easily cleanable, economical to manufacture. It makes possible the complete filling of dispensing guns easily and efficiently without messiness in a matter of a very few seconds. Entrapped air bubbles and improper filling of the guns are eliminated. While the invention has been illustrated in form adapted for cylindrical containers, it is applicable, by modification of the shape of the head and segmental head elements, to other containers of uniform cross section regardless of the shape of the cross section.

I claim:

1. A device for use in filling a dispensing gun with flowable plastic material and comprising a plurality of relatively separable individual elements unattached to each other and assemblable in approximately edgewise relation to each other to provide an annular disc-like member, a relatively rigid head member of less diameter than the external diameter of the disc-like member and detachably engaging the disc-like member at one face and having a central opening aligned with the central opening of the disc-like member, a discharge stem on one of the members having a discharge passage in communication with the opening thereof, said stem being adapted for operative connection to the barrel of a dispensing gun, each of said elements being less in length, in the plane of the disc-like member, than the diameter of the disc-like member, and said head member overlying the major portion of each of the elements when the head member is in engagement with the annular disc-like member.

2. A device for the purposes described comprising an annular head having a generally flat face, a discharge stem on the head and extending from the opposite face thereof, a plurality of relatively flat, non-annular separable individual elements adapted to be assembled in approximately edgewise relationship into an annulus which is of greater diameter than the head and is engaged at one face by the flat face of the head in coaxial relation with the central opening thereof, said head, when in engagement with the separable elements, covering the major portion of the face of each element, and said stem having a discharge passage in communication with the central opening of the annulus and being adapted for connection with the barrel of a dispensing gun.

3. In combination, a container of uniform cross section and having at one end an end opening coaxial with, and of less diameter than, the interior diameter of the container, a piston structure including a head member receivable through said opening and having a central opening, a discharge stem extending from one side of the head and having a discharge passage therethrough in communication with said central opening, said stem being adapted for connection to the barrel of an ejecting gun, a plurality of relatively movable individual

elements receivable individually successively through the end opening independently of the head member and adapted to be repositioned in the container to provide a generally annular head member of substantially the same size and shape as the cross section of the interior of the container and arranged at the side of the piston head member opposite from the stem, with its central opening aligned with the central opening of the piston head member, and movable by the piston head member axially of the container away from the end opening, and means interconnecting the member so as to maintain their central openings in alignment with, and in communication with, each other, and said piston head member overlying the major portion of each of said elements when the members are assembled with the central openings in alignment.

4. A device for the purposes described comprising a plurality of separate individual elements in the form of sectors of an annulus and assemblable in substantially edge to edge abutting relation to each other to provide a relatively flat annular member, an annular head member of less diameter than the annular member and having a flat surface adapted to be juxtaposed detachably against one face of the annular member in coaxial relation to the annular member and overlie the major portion of each of said elements, aligning means on the elements, respectively, cooperating aligning means on the head member interengageable with the aligning means of the elements, a stem discharge means on one of said members and protruding beyond the other face of the annular head member and adapted for connection to the barrel of a dispensing gun to be filled, and said discharge means having a discharge passage in communication with the central opening of the annular member.

5. A device according to claim 4 characterized in that said elements are flat and the stem is on said annular head member.

6. A device for the purposes described and comprising an annular head member, a hollow discharge stem on one face thereof and in communication with the central opening thereof, another annular head member coaxial with the first head member and having a central passage through which the stem extends, a plurality of separate individual head elements movable relative to each other and to the head members into a position in which they provide an annulus which is coaxial with the head members and is of greater diameter than either of the head members, said elements, when in said position, being confined between said head members, and each of said elements being less in overall length, in the plane of the annulus, than the diameter of the annulus.

7. A device for the purposes described comprising a pair of annular head members, hollow stems on the members, respectively, each stem surrounding, and being in communication with, the central passage of its associated head member, the stem of one member being telescopically received in the stem of the other member in one position in which the members are spaced apart axially, a plurality of head elements movable relative to each other and to the members into a position in which they provide an annulus which is coaxial with the annular head members and is of greater diameter than either of the annular head members, and said elements, when

in said position, being accommodated in the space between the annular members.

8. The device according to claim 7 characterized in that the annular head members are duplicates of each other and the stem of each is in the form of a sleeve of uniform wall thickness and which tapers inwardly toward its axis substantially from its junction with its annular head member to its opposite end.

9. A device according to claim 1 characterized in that some of the elements overlap others of the elements at their adjacent margins.

10. A device according to claim 1 characterized in that detachable interengaging means are provided on the members for maintaining the members assembled with the central openings aligned.

11. A device according to claim 10 further characterized in that the detachable interengag-

ing means comprise bosses on the elements, respectively, and passages in the head member respective to the bosses.
